LUGGAGE LATCH

John B. Humphries, Stamford, Conn., assignor to The
Excelsior Hardware Company, Stamford, Conn.

Filed Sept. 27, 1961, Ser. No. 66,901

Term of patent 14 years

(Cl. D50—7)

Fig. 1

FIGURE 1 is a perspective view of a luggage latch showing my new design;

FIGURE 2 is a front view;

FIGURE 3 is a side view;

FIGURE 4 is a top view; and

FIGURE 5 is a phantom outline of my new design taken along the line 5—5 of FIGURE 2.

The dominant features of the design reside in the solid line portions of the figures.

I claim:

The ornamental design for a luggage latch, substantially as shown and described.
